CLAIM

We claim the ornamental design for a bottle, as shown and described.

DESCRIPTION

FIG. 1 is a perspective view of a first embodiment of a bottle showing our new design;

FIG. 2 is a front view of the bottle shown in FIG. 1.

FIG. 3 is a rear view of the bottle shown in FIG. 1.

FIG. 4 is a side view of the bottle shown in FIG. 1.

FIG. 5 is an opposite side view of the bottle shown in FIG. 1.

FIG. 6 is a top view of the bottle shown in FIG. 1.

FIG. 7 is a bottom view of the bottle shown in FIG. 1.

FIG. 8 is a perspective view of the second embodiment of FIG. 1;

FIG. 9 is a front view of the bottle shown in FIG. 8.

FIG. 10 is a rear view of the bottle shown in FIG. 8.

FIG. 11 is a side view of the bottle shown in FIG. 8.

FIG. 12 is an opposite side view of the bottle shown in FIG. 8.

FIG. 13 is a top view of the bottle shown in FIG. 8; and,

FIG. 14 is a bottom view of the bottle shown in FIG. 8.

The present application is directed to the shape and contour of a bottle of the design illustrated in the drawings. Features of the drawings shown in broken lines are not considered part of the design currently sought to be patented.

The broken lines shown in the drawing disclosure are for illustrative purposes only and form no part of the claimed design.
